UNITED STATES PATENT OFFICE.

THOMAS ALLSOP AND WALTER W. SIBSON, OF PHILADELPHIA, PENNSYLVANIA,
ASSIGNORS TO THE PHILADELPHIA DRYING MACHINERY COMPANY, OF PHILA-
DELPHIA, PENNSYLVANIA, A CORPORATION OF PENNSYLVANIA.

DRYING APPARATUS.

1,355,117.

Specification of Letters Patent. Patented Oct. 12, 1920.

Application filed August 4, 1919. Serial No. 315,122.

To all whom it may concern:

- Be it known that we, THOMAS ALLSOP and WALTER W. SIBSON, citizens of the United States, residing in the city and county of Philadelphia and State of Pennsylvania, have invented certain new and useful Improvements in Drying Apparatus, whereof the following is a specification, reference being had to the accompanying drawings.
- 10 The invention relates to drying apparatus usually known as "Tunnel truck driers," wherein the articles to be dried are advanced through the apparatus under the support of one or more series of wheeled trucks.
- 15 The invention is directed more particularly to a unique circulating system for apparatus of the above type, whereby the air within is directed over a series of independent courses, so as to establish a series of separate and independent circulatory zones through which the supporting trucks pass in succession, during the drying operation.

The invention is further directed to means whereby the atmospheric conditions 25 in the several circulatory zones may be independently maintained at different degrees of temperature and humidification, so that the articles under treatment may be subjected to gradual changes as they are advanced through the apparatus.

The invention also provides for the continual displacement of a proportionate amount of the recirculated air in each circulatory zone, so that a corresponding 35 quantity of fresh air may at the same time be admitted, and the entire volume thus changed at intervals.

The invention also includes certain other novel features of construction and arrangement which will be better understood from the detailed description which follows.

In the accompanying drawings, Figure I, is a plan view of a drying apparatus conveniently embodying our invention, certain 45 portions having been broken away to more clearly illustrate details of the interior.

Fig. II, is a side elevation of the receiving end of the apparatus, also having a portion shown in broken-away section, and

50 Fig. III, is a cross sectional view of the device, as viewed in the direction of the arrows III—III, in Fig. I.

In its preferred form, our invention comprises an extensive inclosure 1, having the 55 quadrangular cross sectional configuration

best shown in Fig. III. The length of the apparatus is such as to accommodate one or more series or files of wheeled trucks 2, guided upon the tracks 3—3, running longitudinally through the inclosure. At the 60 left hand, or receiving end (Figs. I and II), the inclosure is provided with a door diagrammatically indicated at 5, which may be either of the hinged or sliding type, so as to be capable of being readily opened and 65 closed to permit the passage of the trucks. While said trucks may be advanced either manually or automatically, in large apparatus of the type to which our invention pertains, it is preferable to resort to the latter 70 method. For accomplishing this purpose, we have accordingly shown conventionally in Fig. I, a feeding mechanism in the form of a series of sprocket chain devices 6, corresponding in number to that of the tracks 75 and occupying central positions with respect thereto. The feeding mechanism is driven from an overhead power shaft 7, the motion of the latter being transmitted through a belt connection 8, and in turn reduced through worm gears 9. The intermittent control may be effected by any suitable means (not shown), and since this mechanism forms no part of the present invention, further reference thereto is 80 deemed unnecessary.

As new trucks are advanced into the inclosure, the preceding units in the several series or files, are bodily shifted so that the leading trucks are discharged from the apparatus at the farther end. At this end, the inclosure is provided with a door 10, similar to that described in connection with the receiving end of the inclosure.

Referring now to Fig. III, it will be 95 noted that the trucks are accommodated within the inclosure with ample provision on each side to form longitudinal passages 11 and 12, and, as shown in Figs. I and II, the trucks are provided with solid vertical 100 ends 13 so that as they are arranged in serial sequence within the inclosure, a number of transverse channels extending between the side passages are automatically established. It is to be further noted that the 105 interior of the inclosure is so arranged that a series of fans 15, register with the alternate rows of transverse channels formed by the trucks.

Each of the fans is set within a circular 110

shroud 16, which forms part of a partition 14, having a width corresponding to that of the trucks and extending from the floor to the ceiling of the inclosure.

5 Said partitions are also formed with lateral end extensions 17-17, which serve as continuations of the truck ends, when the latter are properly positioned in the inclosure, and are functional in preventing short 10 circuiting of the air at these points.

The truck channels, intermediate those just described, register with the spaces 18, between the fan partitions, so that each pair of adjacent transverse channels determines 15 the circuit of the air propelled by the fan with which they are immediately associated, the side passages 11 and 12, serving as common means for otherwise completing the several independent circuits.

20 In order to prevent further short circuiting of the air through the clearance space above the trucks, we have provided longitudinally running baffle plates 19-19, at each side of the inclosure, said plates being suspended 25 from angle beams 20-20, which form part of the skeleton of the apparatus. For a similar reason, we have provided baffles 21-21, at the bottom of the inclosure. These are of an even height with the floors 30 of the trucks. In this way, the air circulation is confined directly to the transverse channels established by the positioning of the trucks.

Located within the passage 11, and arranged 35 in alternation with the fans 15, are a series of heating coil banks 22, one for each circulatory zone. These coil banks are supplementary to a similar series of larger coils 23, in the passage 12, at the opposite side of 40 the inclosure. Both sets of heating coils are provided with individual regulating valves 25.

Similarly arranged at each side of the apparatus, are a series of humidifying devices 45 26 and 27, respectively, also having individual regulating valves 28.

In addition to the auxiliary appurtenances just described, we have provided, at each circulatory zone, for the admission of a 50 certain amount of fresh air and a corresponding discharge of the quantity thus displaced from the interior. In the drawings, the inlets are shown at 29 adjacent the centers of the fans while the outlets are shown 55 as openings 30, in the roof of the structure.

In order to prevent the loss of a certain amount of circulation due to the opening of the doors at both ends of the apparatus, in the course of the interchange of trucks, we 60 have provided at these regions, slatted partitions 31-31 and 32-32, which respectively lie within the region of the end circulatory zones, (see Figs. I and II). These slatted partitions offer considerable resistance, so 65 that the flow of the air is rendered sluggish

and the amount of escape thus reduced in proportion. The several fans constituting the means by which the circulation is effected may be driven in any convenient manner, such as, for example, the belting system indicated comprehensively at 33, in Fig. I. Such systems are of such well known construction that further description is not necessary in connection with the present invention. 75

The operation of the apparatus is as follows:

Referring to Fig. I, it will be observed by tracing the course of the arrows there shown, that the air in each circulatory zone is blown 80 by the fan 15, across the inclosure under the guidance of the registering channel formed by the trucks, thereby coming into intimate contact with the material or articles carried thereon. The circulation then passes through 85 passages 12, to the return channel established by the trucks immediately adjacent the left of those first referred to, and the circuit is finally completed to the suction side of the fan through the passage 11. In the course of 90 its circuit in each zone, the air first encounters the heating coils 23, and humidifying device 27, in the passage 12, and the heating and humidification thus obtained is boosted further on in the circuit when the heating 95 coils 22, and humidifying device 26, in the opposite channel 11, are encountered. Thus by the construction herein set forth it will be seen that the air within the inclosure is circulated over a number of separate and 100 distinct courses, each having its own independently regulatable heating and humidifying system, so that different atmospheric conditions may be maintained in the various circulatory zones, such conditions being 105 maintained and controlled through the aid of recording instruments, such as indicated at 35-35, in Fig. II. This feature of maintaining different atmospheric conditions throughout the length of the inclosure is of 110 utmost importance in connection with the drying of such articles as china, porcelain, crockery, etc., for example. It has been found advantageous in practice in accomplishing the best results, that at the receiving 115 end of the machine, the temperature should be lowest and the humidification highest, and at the finishing end of the machine, the conditions should be exactly reversed, and further that the regulations in 120 the intermediate portions of the apparatus be such as to bring about a gradual change within the extremes mentioned.

The even drying of the articles is further enhanced by the fact that at each step of the 125 advance of the truck series, the direction of impingement of the air is reversed. In other words, in one position, the truck serves as a direct registering channel for the fan, while in the next position, it serves as a re- 130

turn, as a consequence of which the direction of flow of the air is reversed as above noted.

Having thus described our invention, we claim:

5. 1. A drying apparatus comprising an inclosure adapted to receive carriers for the goods to be dried; a series of such carriers having vertical ends forming in the inclosure a number of transverse channels; and
10 means coöperating with said channels to establish, along the length of the apparatus, a series of independent air circulatory zones.

2. A drying apparatus comprising an inclosure adapted to receive carriers for the goods to be dried; a series of carriers having vertical ends whereby the inclosure is subdivided into a number of transverse channels; coöperative means whereby a series of independent air circulatory zones are established along the length of the apparatus through the aid of the channeling afforded by the carriers; separate heating devices and humidifying devices located in each air circulatory zone; and independent
25 means for regulating said heating and humidifying devices, so that varying atmospheric conditions may be maintained in different parts of the inclosure.

3. A drying apparatus comprising an inclosure adapted to receive carriers for the goods to be dried; a series of carriers having vertical ends whereby the inclosure is subdivided into a number of transverse channels; coöperative means whereby a series of independent air circulatory zones are established along the length of the apparatus through the aid of the channeling afforded by the carrier; and means located at the region of each circulatory zone for the admission of a quantity of fresh air and the discharge of a corresponding amount of the recirculated air.

4. A drying apparatus comprising an inclosure adapted to receive carriers for the goods to be dried; a series of such carriers having vertical ends forming in the inclosure a number of transverse channels; and means coöperating with said vertical ends to circulate air in a number of independent courses, along the length of the apparatus, each comprising adjacent channels.

5. A drying apparatus comprising a series of carriers for the articles to be dried and an inclosure of such length as to be capable of accommodating said series of carriers, and of such width as to provide a longitudinal passage at each side of the series of carriers, said carriers having vertical ends whereby a number of transverse channels
60 are formed between the longitudinal side passages; in combination with means for circulating the air at separate zonal regions along the length of the apparatus, the circuit in each instance being determined by

adjacent channels afforded by the carriers, 65 and otherwise completed by the common longitudinal side channels of the inclosure.

6. A drying apparatus comprising a series of carriers for the articles to be dried and an inclosure of such length as to be capable 70 of accommodating said series of carriers, and of such width as to provide a longitudinal passage at each side of the series of carriers, said carriers having vertical ends whereby a number of transverse channels are 75 formed between the longitudinal side passages; in combination with a series of fans located in one of the side spaces, said fans being adapted to register with the alternate transverse channels, so that the air is circu- 80 lated over a number of zonal courses along the length of the apparatus, the course of the circulation in each instance being determined by the adjacent transverse channel and otherwise completed by the common lon- 85 gitudinal side passages.

7. A drying apparatus comprising an inclosure adapted to receive carriers for the goods to be dried; a series of carriers having vertical ends whereby the inclosure is sub- 90 divided into a number of transverse channels; coöperative means whereby a series of independent air circulatory zones are established along the length of the apparatus through the aid of the channeling afforded 95 by the carriers; doors protecting the ends of the inclosure; and means located adjacent said ends for minimizing the escape of the circulated air from the interior of the apparatus when the doors are opened to permit 100 interchange of the trucks.

8. A drying apparatus comprising an inclosure adapted to receive carriers for the goods to be dried; a series of carriers having vertical ends whereby the inclosure is 105 subdivided into a number of transverse channels; coöperative means whereby a series of independent air circulatory zones are established along the length of the apparatus through the aid of the channeling afford- 110 ed by the carriers; doors protecting the receiving and delivery ends of the inclosure; and slatted partitions located at each side of the apparatus adjacent said doors, and adapted to throttle the circulation of the air 115 at these points to minimize the escape of the circulated air from the interior of the apparatus when the doors are opened to permit the interchange of trucks.

In testimony whereof, we have hereunto 120 signed our names at Philadelphia, Pennsylvania, this first day of August, 1919.
